Primary Examiner—Cathron C Brooks*Assistant Examiner*—Karen E Kearney(74) *Attorney, Agent, or Firm*—Banner & Witcoff, Ltd.(57) **CLAIM**

The ornamental design for an icon for a display screen, as shown and described.

DESCRIPTION

FIG. 1 is a front view of an icon for a display screen showing our new design; and,

FIG. 2 is an additional front view thereof, showing additional unclaimed subject matter.

The broken line showing of the rectangular boxes in FIG. 2 and the display screen forms no part of the claimed design.
